DESIGN FOR A DRESS

Betty Kessler, New York, N. Y.

Application November 16, 1938, Serial No. 81,128

Term of patent 3½ years

To all whom it may concern:

Be it known that I, Betty Kessler, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the specific dress disclosed of the specific embroidery on the waist, sleeve, yoke, and skirt portions as shown.

I claim:

The ornamental design for a dress, substantially as shown and described.

BETTY KESSLER.
